UNITED STATES PATENT OFFICE

159,139

BOTTLE SEAL CUTTER

Frank Cicero, Kingston, Pa.

Application June 3, 1948, Serial No. 146,741

Term of patent 3½ years

(Cl. D44—29)

To all whom it may concern:

Be it known that I, Frank Cicero, a citizen of the United States of America, residing at Kingston, in the county of Luzerne, in the State of Pennsylvania, have invented a new, original, and ornamental Design for a Bottle Seal Cutter, of which the following is a specification, reference being had to the accompanying drawings, forming a part thereof.

Figure 1 is a perspective view of a bottle seal cutter, showing my new design;

Figure 2 is a view in side elevation of the bottle seal cutter shown in Figure 1;

Figure 3 is a bottom plan view of the bottle seal cutter shown in Figure 1; and

Figure 4 is an end view of the bottle seal cutter shown in Figure 1.

I claim:

The ornamental design for a bottle seal cutter, substantially as shown.

FRANK CICERO.
